UNITED STATES PATENT OFFICE.

EDWARD P. RAUSCHER, OF COLUMBUS, OHIO.

MINING-MACHINE.

SPECIFICATION forming part of Letters Patent No. 752,180, dated February 16, 1904.

Application filed June 20, 1903. Serial No. 162,441. (No model.)

To all whom it may concern:

Be it known that I, EDWARD P. RAUSCHER, a citizen of the United States, residing at Columbus, in the county of Franklin and State 5 of Ohio, have invented certain new and useful Improvements in Mining-Machines; and I do hereby declare the following to be a full, clear, and exact description of the invention, such as will enable others skilled in the art to which 10 it appertains to make and use the same.

This invention, relating to mining-machines of the pick type, has for its object to provide a cheap, simple, strong and effective construction which shall not be as liable to injury by 15 falling coal or rock and rough handling as those heretofore in use.

A further object is to provide improved means for effecting the rotation of a reciprocable pick.

20 Other objects will appear from the following description.

The features of novelty are pointed out in the claims.

In the accompanying drawings, illustrating one embodiment only of the invention, Figure 1 is a top plan view, the cap for covering the driving-pinion and master-gear being removed. Fig. 2 is mainly a side elevation with parts in section. Fig. 3 is a detail of 25 the pick, showing it coupled with the plunger of pick-stock. Fig. 4 is a view of the operative end of the pick as seen from a plane at right angles to that used in Fig. 3. Fig. 5 is a horizontal sectional view of the rear bearing for 30 the plunger. Fig. 6 is a rear elevation of the rear bearing. Fig. 7 and Fig. 8 are rear and side elevations, respectively, of the forward bearing for the plunger. Figs. 9 and 10 are rear and side views, respectively, of the trunnions upon which the wheels to support the 35 machine are journaled. Fig. 11 shows the swivel connection between the rear end of the plunger or pick-stock and pitman.

40 1 and 1^a are upper and lower frame bars or 45 beams, respectively, extending longitudinally of the machine.

50 2 is the casing for containing the motor or driving apparatus. This is indicated to be an electric motor; but other kinds of apparatus 55 can be employed. The frame bars or beams 1 and 1^a are secured at their rear ends in lugs

2^a and 2^b on the casing 2 and at their forward ends in sockets or lugs 3^a and 3^b in the piece 3 to contain the forward bearing for the plunger or pick-stock. The frame bars or beams 1 and 1^a are shown to lie parallel to each other in their rear portions or for about half their length and to converge toward each other in their forward portions, the forward extremities being focused in the piece 3, containing 60 the forward bearing.

4 designates the bracket or piece containing the rear bearing for the plunger. This is held between the four frame-bars 1 1 and 1^a and 1^a by means of clamps 4^a, embracing the bars 65 and clamped to the bracket 4 by bolts. The bracket 4 and the clamps 4^a serve also to brace and retain the frame-bars 1 and 1^a in stable position near their middles.

5 designates the tool-stock or plunger. This 70 has a sliding fit in a collar-bearing 6, secured in the bracket 4. The collar-bearing has on its outer side a spherical or ball contour fitting in a socket corresponding in contour on the inner side of the bracket 4 and at the end of a 75 nut 4^b, threaded into the bracket to secure the collar-bearing in the bracket. The collar-bearing 6 has secured to or cast with it a toothed gear 6^a. This collar-bearing also has a key or spline 6^b to engage a longitudinal key- 80 way or groove 5^a in the plunger or pick-stock, so that the latter can be rotated axially while reciprocating longitudinally. Room will be left in the bracket 4 at each side of the collar-bearing to permit the bracket to rock universally on the collar-bearing. In other words, 85 should the frame be distorted by falling coal or rock the alignment of the collar-bearing will not be disturbed. The bearing for the forward end of the pick-stock can be in all respects like that just described in connection with the bracket 4, except, of course, that the toothed gear 6^a need not be duplicated there. The bearing of the pick-stock in the bracket 4, as well as that in the part 3, might appropriately be termed a "universal" or "ball-and-socket" bearing.

90 7 designates the master driving-gear. This is supported on a web or shelf projecting forward from the casing 2. The lower end of 100 the shaft 7^a of the master-gear is furnished with a crank 7^b. The master-gear is driven

by pinion 8 on the power-shaft 8^a. Connected with the crank 7^b is a pitman 7^c, and interposed between the pitman 7^c and the rear end of the pick-stock 5 is a spring 9, the ends of which are hooked in links 10, said links being caught under hooks 11^a on a collar 11, swiveled on the rear end of the pick-stock 5. The swiveled connection between the spring and the plunger is illustrated in detail in Fig. 11. 5 This connection is made swiveled, so that the pick-stock in the particular construction shown can be axially rotated without rotating the spring or crank-rod. The collar 11 is shown to be held on the pick-stock by means of a nut 5^b, which can be suitably locked to prevent it from turning off. 10 The swivel connection just described can be located between the spring 9 and the pitman 7^c instead of between the spring and pick-stock. 15 Handles 12 on the casing 2 for convenience in moving, holding, and directing the machine in operation are shown to be provided. 20 The toothed gear 6^a is shown to be engaged by a pinion 13 on a shaft 13^a, reaching rearward to the rear of the machine within convenient distance of the operator, a hand-wheel 13^b being provided for turning the shaft, so that the position of the cutting end of the pick can be varied. 14 designates the pick. 25 This preferably is removably coupled by a coupling 14^a to the pick-stock 5. The coupling 14^a is made with a transverse hole 14^b, into which a drift may be driven to loosen the pick when it is desired to remove it. 30 35 15 designates a trunnion for one of the carrying-wheels 16. The trunnion projects laterally from a base 15^a, and the latter has perforated ears 15^b to permit the base to be slipped on and secured to the frame-bars 1 and 1^a. 40 The master-gear 7 and pinion 8 can be protected from falling things by an appropriate hood 2^d, removably attached to the casing 2. The operation, which can be readily understood from the foregoing description and the accompanying drawings, is very simple. The machine is moved up to a wall of coal and the pick directed toward the place in the wall to be cut. The rotation of the master-wheel 45 effects, through the crank of its shaft and the pitman, a rectilinear reciprocation of the tool-stock and pick. The impact of the pick breaks up the coal, the machine being moved on its wheels to make the cut as desired. While 50 the pick is reciprocating the cutting end thereof can be varied in its position, as before stated. 55 It will be observed by those skilled in machinery that the frame-bars 1 and 1^a can be considerably bent or distorted without materially interfering with the operation of the machine. This is because the universal bearings in the bracket 4 and part 3 are maintained in their horizontal or normal position, even though the surrounding frame be moved 60 to some extent out of its primary position. 65

What I claim, and desire to secure by Letters Patent, is—

1. In a mining-machine of the pick type, the combination of a frame, a socket-bearing supported in the frame, a ball universally movable in the socket-bearing, a pick-stock passing through and reciprocable in said ball, and means for mechanically rotating the pick-stock. 70

2. In a mining-machine of the pick type, 75 the combination of a frame, a reciprocating pick-stock supported therein, and universal bearings in the frame for the rear and forward portions of the pick-stock.

3. In a mining-machine of the pick type, 80 the combination of a frame, a reciprocating and rotatable pick-stock, a universal bearing in the frame supporting said pick-stock, said bearing connected with said pick-stock to rotate therewith and having a gear thereon, a 85 rearwardly-extending shaft supported in the frame having thereon a pinion to engage the aforesaid gear.

4. In a mining-machine of the pick type, 90 the combination of a frame, a reciprocating and rotatable pick-stock, a universal bearing in the frame supporting said pick-stock, a gear connected with said pick-stock, a rearwardly-extending shaft supported in the frame having a pinion thereon to engage the 95 aforesaid gear.

5. In a mining-machine of the pick type, the combination of a motor-casing 2, a bearing-piece for the pick-stock, a ball supported in said bearing-piece and universally movable 100 therein, frame-bars 1 and 1^a connecting said motor-casing and bearing-piece, a pick-stock supported in the ball and reciprocable therein and means for reciprocating the pick-stock. 105

6. In a mining-machine of the pick type, 110 the combination of a motor-casing 2, a bearing-piece 3, frame-bars 1 and 1^a, connecting said motor-casing and bearing-piece, a bearing-bracket 4, and a reciprocable pick-stock supported in the bracket 4 and bearing-piece 115 3, and means for reciprocating the pick-stock. 120

7. In a mining-machine, the combination of frame-bars 1 and 1^a, a trunnion for a carrying-wheel thereof comprising a base portion adapted to engage said bars 1 and 1^a, and a spindle 115 projecting from said base to receive the wheel.

8. In a mining-machine of the pick type, the combination of a frame, a bearing-support in the frame, a bearing universally movable in the bearing-support, a pick-stock passing through and reciprocable in said bearing, and means for mechanically rotating the pick-stock. 125

In testimony whereof I affix my signature in presence of two witnesses.

EDWARD P. RAUSCHER.
